CLAIM

The ornamental design for a flask lid, as shown and described.

DESCRIPTION

FIG. 1 is a front perspective view of a flask lid showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another front perspective view of the flask lid of FIG. 1 where the flask lid is shown in a configuration of use. The broken lines in the drawings depict portions of the flask lid that form no part of the claimed design.
